UNITED STATES PATENT OFFICE.

HENRY K. SANDELL, OF CHICAGO, ILLINOIS, ASSIGNOR TO HERBERT STEPHEN MILLS,
OF CHICAGO, ILLINOIS.

DESIGN FOR A PHONOGRAPH TONE-ARM.

58,834.

Specification for Design.

Patented Aug. 30, 1921.

Application filed October 3, 1919. Serial No. 328,295. Term of patent 14 years.

To all whom it may concern:

Be it known that I, HENRY K. SANDELL, a citizen of the United States, residing at Chicago, county of Cook, and State of Illinois, have invented a new, original, and ornamental Design for a Phonograph Tone-Arm, of which the following is a specification, reference being had to the accompanying drawing, forming a part hereof, in which:

Figure 1 of the drawings is a side elevation of the phonograph tone arm, and

Fig. 2 is a plan view thereof.

The supporting members for the tone

arm, indicated upon the drawing by the numerals 10 and 11, are not essential parts of the tone arm and are not to be regarded as component elements of the design.

The design for tone arms illustrated is characterized in that the central portion is constricted for a substantial portion of its length and terminates in relatively enlarged ends.

I claim:

The ornamental design for a phonograph tone arm as shown and described.

HENRY K. SANDELL.
